US00D938752S

(12) **United States Design Patent** (10) **Patent No.:** **US D938,752 S**
(45) **Date of Patent:** **** Dec. 21, 2021**

(54) **DISPENSER**

- (71) Applicant: **CASCADES CANADA ULC**,
Montreal (CA)
- (72) Inventors: **Manuel Léveillé**, Montreal (CA);
Olivier Patry, Montreal (CA); **Nathalie Comeau**, Candiac (CA)
- (73) Assignee: **CASCADES CANADA ULC**, Kingsey Falls (CA)
- (**) Term: **15 Years**
- (21) Appl. No.: **29/750,283**
- (22) Filed: **Sep. 11, 2020**

Related U.S. Application Data

- (62) Division of application No. 29/647,684, filed on May 15, 2018, now Pat. No. Des. 899,132.

(30) **Foreign Application Priority Data**

- Feb. 23, 2018 (CA) 179934
- (51) **LOC (13) Cl.** **20-02**

Primary Examiner — Nathan M Johnston

(74) *Attorney, Agent, or Firm* — Marshall, Gerstein & Borun LLP

(57) **CLAIM**

The ornamental design for dispenser, as shown and described.

DESCRIPTION

FIG. 1 is a perspective view of a dispenser in accordance with the inventive design;

FIG. 2 is a front elevation view of the dispenser shown in FIG. 1;

FIG. 3 is a rear elevation view of the dispenser shown in FIG. 1;

FIG. 4 is a top plan view of the dispenser shown in FIG. 1; FIG. 5 is a bottom plan view of the dispenser shown in FIG. 1;

FIG. 6 is left-side elevation view of the dispenser shown in FIG. 1; and,

FIG. 7 is right-side elevation view of the dispenser shown in FIG. 1.

The dashed lines immediately adjacent to the shaded areas in the figures represent the boundaries of the claimed design. The dashed lines in the figures illustrate the portions of the dispenser that form no part of the claimed design. None of the broken lines form any part of the claimed design.

1 Claim, 7 Drawing Sheets
